UNITED STATES PATENT OFFICE.

HARRY E. KATZENMOYER, OF READING, PENNSYLVANIA, ASSIGNOR TO SCOTT AND WILLIAMS, INC., OF NEW YORK, N. Y., A CORPORATION OF MASSACHUSETTS.

TUCKING ATTACHMENT FOR KNITTING MACHINES.

1,404,124.

Specification of Letters Patent. Patented Jan. 17, 1922.

Application filed May 8, 1920. Serial No. 379,793.

To all whom it may concern:

Be it known that I, HARRY E. KATZENMOYER, a citizen of the United States of America, residing in the city of Reading, in the county of Berks, in the State of Pennsylvania, have invented certain new and useful Improved Tucking Attachments for Knitting Machines, of which the following is a specification.

10 My invention consists of an improved tucking attachment for knitting machines, more particularly adapted for use in the production of the fashioned seamless stocking which forms the subject of the Scott Patent 15 No. 1,233,714, dated July 17, 1917. Said patent shows a seamless stocking having at the back of the leg two rows of distinguishing marks, which are preferably formed by tuck stitches, that is, loops held up in given 20 wales and courses.

A convenient means for producing tuck stitches is that disclosed in the Brown Patent 642,579, February 6, 1900, and comprising the provision of needles with longer 25 latches for knitting those wales in which the tuck stitches are to be produced than in the case of the needles for the wales in which no tuck stitches are to be made, and in connection therewith is provided a movable 30 clearing cam and mechanism to operate the cam so that at some courses all the needles will be moved to clear the stitches and at other times the needles will be projected only far enough to clear the stitches on the 35 short latch needles and not those on the long latch needles. In the accompanying drawings I have shown a tuck-producing means of this type for illustration of my invention, but I do not limit myself to that type of 40 tuck-producing means.

My invention consists more particularly in the provision of improved means whereby tuck stitches may be formed in one or a few successive courses at a time with a relatively 45 larger number of intervening plain courses.

In the case of the machine illustrated this is controlled by the pattern means through mechanism operating on the movable clearing cam.

50 In the accompanying drawings I have shown my improved tucking mechanism for application to one of the well known Scott and Williams machines, employing a rotat-

ing needle cylinder and stationary cam cylinder.

55

Fig. 1 is a front elevation of my attachment as applied to said mechanism;

Fig. 2 is a side elevation of a part thereof;

Fig. 3 is a view of a detail;

Fig. 4 is a plan view to illustrate the location of, and devices for acting on, the clearing cam;

60

Fig. 5 is an inside face view of the stitch cams;

65

Fig. 6 illustrates long and short latch needles.

70

In the case illustrated I have shown the leading stitch cam 50 as the movable clearing cam, pivoting it at 51 and providing its free end with a pin 52 projecting to the exterior of the cam cylinder. This pin 52, as seen in Fig. 4, rests upon the outer end of a lever 49 pivoted at 48 to a suitable bracket on the bed plate 10 of the machine, and connected at its other end to a rod 47 which is vertically guided in the bed plate with its lower end (Fig. 1) immediately over a rotatable cam 8.

75

When the rod 47 is not held in an elevated position by this cam 8, this rod will stay in its lower position by gravity resting on the hub of the cam, and will elevate the end of the lever 49 which supports the free end of the switch cam 50 to keep the latter in its higher position shown by full lines 80 in Fig. 5. When this cam is held in that position, the long latch needles as well as the short latch needles will be projected far enough to clear their stitches. But when the cam 8 acts to raise the rod 47, the cam 50 will drop to the position indicated by dotted lines in Fig. 5, where the long latch needles will not be projected far enough to clear the loops, but the short latch needles 85 will clear them. The pressure of the butts of the arriving needles may be depended on to cause the cam 50 to drop to the lower position when the lever 49 permits, or a spring 46 (Fig. 4) carried by the arm 49 and bearing on the upper side of the pin 52 90 may be employed if desired.

95

The above mentioned controlling cam 8 is mounted to turn upon a stud 5, carried by the arm 4 of a bracket 2, which is secured to the frame 1 of the machine. Secured to 100 or formed in one with this cam 8 is a ratchet

wheel 6, illustrated as provided with eight teeth, one of which, shown by the dotted lines back of the cam 8, (Fig. 2), is lower in height than the others. A friction spring washer w may be interposed between the bracket 2 and the ratchet 6.

To act upon this ratchet wheel 6, I provide a pawl lever 16 with a spring-pressed pawl 15, Fig. 2. During the operation of 10 the knitting machine this pawl lever is caused to constantly vibrate on its pivot by the action of a spring 19 and a cam 18 on the main shaft of the machine, with which the knitting head rotates in unison, so that 15 so long as the pawl 15 can engage the teeth of the ratchet wheel 6, the latter (and therefore the controlling cam) will be moved to to the extent of one tooth of the ratchet at every revolution of the knitting head.

20 In the case illustrated I have shown the cam 8 (Fig. 2) as of sufficient length to hold the rod 47 elevated for two revolutions of the knitting head and therefore the tuck stitches to be held for two courses, while for 25 the remaining six movements of the ratchet wheel 6 and therefore for six courses of the knitting, the cam 50 will be held elevated to clear the stitches on all the needles and produce plain knitting. Any desired ratio 30 of tuck stitches to plain stitches can be brought about by increasing or decreasing the number of teeth in the ratchet wheel 6 and by increasing or diminishing the length of the cam 8.

35 In combination with the above described mechanism for moving the clearing cam to and from the tucking position at irregular intervals, I provide means under the control 40 of the pattern chain for automatically putting said intermittent tucking mechanism into and out of operation, so that these tuck stitches may be formed only at the desired part of the length of the stocking or other article being knitted.

45 For this purpose I provide means under the control of the pattern chain 21 for holding the pawl 15 out of reach of the low tooth of the ratchet wheel 6 when the intermittent tucking is not to take place. On the pawl 50 15 is provided a pin or other projection 14, over which lies the curved finger 13 of a lever 11 which is pivoted at 12 (Fig. 1) to the arm 3 of the bracket 2. The other end of this lever 11 has pivoted to it a rod 19¹ 55 guided in a bracket 20, on the frame of the machine and having its lower end over the links of the pattern chain 21. A coiled spring s (Fig. 1) is employed to tend to draw this rod 19¹ downwardly towards the 60 pattern chain, but the rod may be held in its elevated position by a latch 25 pivoted at 26 to the frame and having a tooth 32 to engage a not h 33 on the rod (Fig. 3). A spring 26¹ tends to push the latch towards 65 the rod 19¹. The lower end of the latch 25,

however, lies in the path of a pin or pins 34 on the side of the pattern chain 21, (Fig. 1) so that as the pattern chain travels in the direction of the arrow, Fig. 3, this pin 34 coming into contact with the latch 25 70 will disengage the latter from the rod 19¹, and the latter will drop.

When the rod 19¹ is in its upper position and held there by the latch 25, the finger 13 on the lever 11 will hold the vibrating pawl 15 out of engagement with the lowest tooth of the ratchet wheel 6, but not far enough away to prevent engagement of the pawl with the other teeth of the ratchet wheel 16. Consequently when the pawl ceases to operate the ratchet, the cam 8 will be out of contact with the rod 47 and the stitch cam 50 will be in its higher position to cause all 80 the needles to clear the stitches. When, however, the point has been reached where the intermittent tucking is to take place, a pin 34 on the pattern chain 21 (Fig. 1) will contact with the latch 25, throw it free of the rod 19¹, which will drop, and so release the vibrating pawl 15 to engage the lowest 90 tooth of the ratchet as well as the others and turn the cam 8 tooth by tooth to cause the intermittent tucking.

When this intermittent tucking is to cease, a lug 35 (Figs. 1 and 3) on one of the links 95 of the pattern chain, will act upon the lower end of the rod 19¹ to lift it and the latch 25 will at once drop into holding engagement with this rod and latch the latter in its elevated position, and thereby the finger 13 on 100 the lever 11 will depress the pawl 15 to a position where it cannot reach the lowest tooth of the ratchet 6 and this latter will come to a position of rest with cam 8 out of contact with the rod 47, and the clearing 105 cam 50 therefore elevated for plain knitting.

I claim as my invention—

1. A knitting machine having needles, some of which are adapted to be used for 110 tucking, and a movable clearing cam therefor in combination with mechanism for moving said cam to and from the tucking position, said mechanism including a cam to control the clearing cam, a ratchet 115 wheel combined with said controlling cam and having high teeth and a low tooth, a vibrating pawl to actuate said ratchet wheel and means to hold the pawl in the path of the high teeth but out of 120 reach of the low tooth of the ratchet wheel.

2. A knitting machine having needles, some of which are adapted to be used for 125 tucking, and a movable clearing cam therefor in combination with mechanism for moving said cam to and from the tucking position, said mechanism including a cam to control the clearing cam, a ratchet wheel combined with said controlling cam and having high teeth and a low tooth a vi rating 130

pawl to actuate said ratchet wheel, a pattern mechanism and means under the control of a pattern mechanism to hold the pawl in the path of the high teeth but out of reach of the 5 low tooth of the ratchet wheel.

3. A knitting machine having needles, some of which are adapted to be used for tucking and a movable clearing cam therefor in combination with a cam means to

move the clearing cam to and from the tucking position a ratchet wheel combined with said cam means, a vibrating pawl to actuate said ratchet wheel, latch devices to hold the pawl out of action and a pattern mechanism to disengage and engage the latch. 10

In testimony whereof I have signed my name to this specification.

HARRY E. KATZENMOYER.
